UNITED STATES PATENT OFFICE.

GEORGES CLOETENS, OF ST. GILLES, NEAR BRUSSELS, BELGIUM.

REED ORGAN.

Application filed May 3, 1922. Serial No. 558,053.

To all whom it may concern:

Be it known that I, GEORGES CLOETENS, a subject of the King of Belgium, and resident of St. Gilles, near Brussels, Belgium, have

- 5 invented certain new and useful Improvements in Reed Organs; and I do hereby declare the following to be a full, clear, and exact description of the invention, such as will enable others skilled in the art to which 10 it appertains to make and use the same, reference being had to the accompanying drawings, and to letters or figures of reference marked therein, which form a part of this specification.
- 15 The present invention relates to improvements in reed organs with beating reeds, and more particularly to improvements in reed organs with beating reeds of the kind described in my prior United States Patents
- 20 No. 1,095,268 granted on 5, May, 1914, and No. 1,179,504, granted on 18, April, 1916.

The purpose of this invention is to improve upon the organs of the aforesaid patents in order to increase the artistic and 25 musical possibilities of these types of organs and to permit a larger variation in the musical effects, and in the modification of the timbre or tone-quality.

In the reed organs, according to the above 30 mentioned patents, I provide a plurality of beating reeds of different pitch forming a scale disposed along a resonating pipe; an air chest having one or a plurality of casings in communication with said reeds, valves 35 between said reeds and said resonating pipe, controlling the selection of said reeds, and an auxiliary resonating pipe in communication with the prime resonating pipe; a tone slide disposed at the wider part of the prime 40 pipe in order to permit the modification of the sound by controlling the outlet opening of said pipe, and an "echo-bell," placed on foresaid part of the resonating pipe.

The results directed by the present invention 45 are obtained by the following features:

(1) In realizing the communication of the auxiliary resonating pipe, on the side of the wider part of the prime resonating 50 pipe not with this pipe but with the outer air.

(2) In realizing the communication existing between the prime and the auxiliary resonating pipe by a plurality of openings 55 of substantially equal section.

(3) In controlling the outlet of the air

passing through these openings by the displacement of a suitable slide permitting to increase or decrease gradually the section of said openings.

(4) In providing a valve or slide at the outlet opening towards the outer air of said auxiliary resonating pipe, in order to increase or decrease the section of said outlet opening.

(5) In providing an "echo-bell" at the wider part of the auxiliary resonating pipe.

(6) In providing an auxiliary resonating pipe having a substantially conical form, the conicity being of the same direction as 70 that of the prime resonating pipe.

(7) In providing a valve or slide similar to that specified under (4) on the side of the narrow part of the resonating pipes.

(8) In arranging the valves controlling 75 the outlets of the reeds in such a manner that the sound passing through said valves is directed by means of the valves towards the auxiliary resonating pipe, in order to increase considerably the musical value of 80 the sound.

These and further features of the invention will now be described and claimed.

A preferred form of my invention is illustrated in the accompanying drawing, on 85 which:

Fig. 1 is a transverse section through the resonating pipe of an organ embodying the invention.

Fig. 2 is a horizontal section on the line 90 2—2 of Fig. 1.

Fig. 3 is another horizontal section on the line 3—3 of Fig. 1.

Fig. 4 shows an element of the slide on a larger scale.

The type of organ-stop shown at the figures has an air chest 1 having one or a plurality of compartments 2, connected in the well-known manner (not shown) with the usual wind or suction apparatus not 100 illustrated. The reeds 3 are disposed along this air chest which communicates with the resonator by means of the angled conduits 4 whose outlet openings are controlled by the valves, 5. These valves 5 may turn 105 around their axis 6 and are pivoted by means of the keys 7 of the instrument a regulating screw 9 being provided at the extremity 10 of each of said keys. A threaded bolt 11 increases or decreases the section of each of 110 the conduits 4.

The resonator comprises a prime resonat-

ing pipe 12 of pyramidal form, having a rectangular cross section as shown in Fig. 1, and of which the axis is parallel to that of the air chest 1, and an auxiliary 5 resonating pipe 13 of conical form, as shown in Fig. 1. The transverse sections of the two resonating pipes 12 and 13 taper in the same direction and on their outlet openings 14 and 15 are mounted "echo-bells" 16 and 17 10 of suitable form, as shown in Fig. 3.

The prime pipe 12 communicates with the auxiliary pipe 13 by means of a plurality of openings 18 provided along their adjacent lateral faces 19 and 20, these openings 18 having a substantially equal section. 15 A slide 21 controlled by a suitable mechanism 22, is provided with openings 23, as shown in Fig. 4 and can be displaced by translation between the adjacent faces 19 and 20 of pipes 12 and 13. The openings 23 have preferably the substantially triangular form shown in Fig. 4 and the alternate translation of the slide 21 increases or decreases gradually the section of the 25 passage of the sound towards the auxiliary pipe 13. The extreme positions of the slide with respect to the openings 18 assure either the largest section or the narrowest of said openings.

30 At the outlets 14 and 15 of larger section of the two resonating pipes 12 and 13 is provided a common tone-slide 26 to assure the crescendo or decrescendo effect of the instrument, said tone-slide being controlled 35 by a suitable mechanism 27. On another side, the passage of these outlets 14 and 15 may be respectively obstructed by means of valves 28 and 29 pivoting around their axis 30 and 31. Similar valves 32 and 33 may 40 be provided at the narrow outlets 34 and 35 of the pipes 12 and 13, as shown in Fig. 3, each of these valves 28, 29, 34 and 35 being controlled by a separate mechanism 36, 37, 38 and 39.

45 In respect to the perpendicular position of the conduits 4 relatively to the openings 18, the angular displacement of the valves 5 realizes in the pipe 12 a directing plane, conducting the sound towards the openings 50 18 abutting in the auxiliary resonating pipe 13.

The above described improvements with the reeds mounted in the usual manner, enable me to produce the purest notes by air 55 at positive pressure or if operated by suction.

It will be understood that a plurality of similar stops having varying tone qualities may be combined in an organ as is characteristic of that instrument.

60 What I claim is:—

1. A reed organ comprising a resonating pipe of a substantially conical form, a plurality of beating reeds of different pitch forming a scale, an air chest in communica-

cation with said reeds, valves between said reeds and said resonating pipe, an auxiliary resonating pipe, and a plurality of openings of substantially equal section establishing the communication between the two resonating pipes. 70

2. A reed organ comprising a resonating pipe of a substantially conical form, a plurality of beating reeds of different pitch forming a scale, an air chest in communication with said reeds, valves between said reeds and said resonating pipe, an auxiliary resonating pipe, and a plurality of openings of substantially equal section establishing the communication between the two resonating pipes, each of these openings being situated opposite a reed. 75

3. A reed organ comprising a resonating pipe of a substantially conical form, a plurality of beating reeds of different pitch forming a scale, an air chest in communication with said reeds, valves between said reeds and said resonating pipe, an auxiliary resonating pipe having a substantially pyramidal form. 80

4. A reed organ comprising a resonating pipe of a substantially conical form, a plurality of beating reeds of different pitch forming a scale, an air chest in communication with said reeds, valves between said reeds and said resonating pipe, an auxiliary resonating pipe, and a plurality of openings of substantially equal section establishing the communication between the two resonating pipes, a slide allowing the control of the passage-section of aforesaid openings. 95

5. A reed organ comprising a resonating pipe of a substantially conical form, a plurality of beating reeds of different pitch forming a scale, an air chest in communication with said reeds, valves between said reeds and said resonating pipe, an auxiliary resonating pipe, and a plurality of openings of substantially equal section establishing the communication between the two resonating pipes, a slide having a multiplicity of openings, and disposed to slide in front of the said openings for regulating passage through the same. 100

6. A reed organ comprising a resonating pipe of a substantially conical form, a plurality of beating reeds of different pitch forming a scale, an air chest in communication with said reeds, valves between said reeds and said resonating pipe, an auxiliary resonating pipe and a plurality of openings establishing the communication between the two resonating pipes, the auxiliary resonating pipe communicating by its extremity corresponding at the wider part of the prime resonating pipe with the outer air. 115

7. A reed organ comprising a resonating pipe of a substantially conical form, a plurality of beating reeds of different pitch forming a scale, an air chest in communica-

- tion with said reeds, valves between said reeds and said resonating pipe, an auxiliary resonating pipe and a plurality of openings establishing the communication between the two resonating pipes, the auxiliary resonating pipe communicating by its extremity corresponding at the wider part of the prime resonating pipe with the outer air, means for regulating the outlet opening with the outer air of the auxiliary resonating pipe. 8. A reed organ comprising a resonating pipe of a substantially conical form, a plurality of beating reeds of different pitch forming a scale, an air chest in communication with said reeds, valves between said reeds and said resonating pipe, an auxiliary resonating pipe and a plurality of openings establishing the communication between the two resonating pipes, the auxiliary resonating pipe communicating by its extremity corresponding at the wider part of the prime resonating pipe with the outer air, an "echo-bell" being disposed across the mouth of said auxiliary resonating pipe. 9. A reed organ comprising a resonating pipe of a substantially conical form, a plurality of beating reeds of different pitch forming a scale, an air chest in communication with said reeds, valves between said reeds and said resonating pipe, an auxiliary resonating pipe and a plurality of openings establishing the communication between the two resonating pipes, the auxiliary resonating pipe communicating with the outer air at the narrow part of the prime resonating pipe, and means for controlling said communication opening. 10. A reed organ comprising a resonating pipe of a substantially conical form, a plurality of beating reeds of different pitch forming a scale, an air chest in communication with said reeds, valves between said reeds and said resonating pipe, an auxiliary resonating pipe, and a plurality of openings of substantially equal section establishing the communication between the two resonating pipes, each of these openings being situated opposite a reed and means for directing towards said openings, the sounds passing through the valves disposed between the reeds and the resonating pipe. 11. A reed organ comprising a resonating pipe of a substantially conical form, a plurality of beating reeds of different pitch forming a scale, an air chest in communication with said reeds, valves between said reeds and said resonating pipe, an auxiliary resonating pipe, and a plurality of openings of substantially equal section establishing the communication between the two resonating pipes, each of these openings being situated opposite a reed, the outlet openings of the reeds in the resonating pipe being disposed perpendicular to the communicating openings existing between the two resonating pipes, and the valves disposed between said outlet openings and the resonating pipe, being pivoted around their axis, thus conducting the sounds leaving said outlet openings towards aforesaid communicating openings.

In testimony whereof I affix my signature in presence of two witnesses.

GEORGES CLOETENS.
